UNITED STATES PATENT OFFICE

136,933

DESIGN FOR AN APRON

Helene Pons, New York, N. Y.

Application October 18, 1943, Serial No. 111,416

Term of patent 3½ years

To all whom it may concern:

Be it known that I, Helene Pons, a citizen of the United States, residing at New York city, in the county and State of New York, have invented a new, original, and ornamental Design for an Apron, of which the following is a specification, reference being had to the accompanying drawing, forming a part thereof.

The figure is a plan view of an apron, showing my new design.

I claim:

The ornamental design for an apron, substantially as shown.

HELENE PONS.
